R.B. Harrison

Track-Layer.

No 18,144.

Patented Sept. 8, 1857.

UNITED STATES PATENT OFFICE.

RICHARD B. HARRISON, OF VICKSBURG, MISSISSIPPI.

MACHINE FOR RAMMING UNDER THE CROSS-TIES OF RAILROADS.

Specification of Letters Patent No. 18,144, dated September 8, 1857.

To all whom it may concern:

Be it known that I, RICHARD B. HARRISON, of Vicksburg, in the county of Warren and State of Mississippi, have invented a Mov-
able Machine for Ramming Earthy Matter
Under the Cross-Ties of Railroads; and I
do hereby declare that the following is a
full and exact description thereof, reference
being had to the accompanying drawings,
10 making a part of this specification, Figure 1
being a side view of said machine standing
upon the section of a railroad; Fig. 2, a top
view of the same, and Figs. 3 and 4 are por-
tions of the machine detached.

15 Similar letters indicate like parts in each
drawing.

My movable machine for ramming earthy
matter under the cross-ties of rail-roads, is
composed in part, of a platform car whose
20 axles are of such a length that its wheels
h, h, will run upon the rails of the rail-road
whose cross-ties are to be leveled up by
means of the employment of said machine.

The rams C, C, should be of such a length
25 that they can be freely reciprocated up and
down on each side of the cross-ties *i, i*, with-
out coming in contact with the rails *g, g*.
The said rams are securely fastened to the
vertical handles B, B, which pass through
30 oblong apertures near the center of the plat-
form A, of the car, and their upper ends are
jointed to the actuating levers E, E. At
their inner ends, the levers E, E, are re-
ceived between the standards D, D, and
35 work upon a connecting fulcrum pin which
passes through the said standards.

The rams C, C, may be so guided in their
movements, by means of adjustable springs,

or their equivalents, that the said movements
will force the earthy matter from both sides 40
under the cross-ties, in the most thorough
and efficient manner.

The machine may be retained in a proper
position for operating upon any given cross-
tie, by means of hooks *f, f*, which descend 45
from the sides of the machine and embrace
the rails, as shown in Fig. 1; or any other
suitable device may be employed for secur-
ing the machine in a stationary position.

In operating the machine, one or two 50
men may be stationed upon the platform A,
to operate each of the rams, and another
man may be employed for moving the ma-
chine forward from one cross-tie to another
at proper intervals, and securing the ma- 55
chine in a stationary position while the men
upon the platform may be operating the
rams.

What I claim as my invention and desire
to secure by Letters Patent, is— 60

My movable machine for ramming earthy
matter under the cross-ties of rail-roads;
said machine being composed of reciprocat-
ing rams and suitable actuating levers com- 65
bined with a platform-car, substantially as
herein set forth.

The above specification of my new and
improved machine for ramming earthy mat-
ter under the cross-ties of railroads signed
and witnessed this 16th day of March, 1857. 70

RICHARD B. HARRISON.
